UNITED STATES PATENT OFFICE.

ELMER E. KAUFMAN, OF CHICAGO, ILLINOIS.

KEY.

SPECIFICATION forming part of Letters Patent No. 596,270, dated December 28, 1897.

Application filed January 18, 1897. Serial No. 619,551. (No model.)

To all whom it may concern:

Be it known that I, ELMER E. KAUFMAN, of Chicago, Illinois, have invented certain new and useful Improvements in Keys, of which 5 the following is a specification.

My invention relates to door-keys and will be fully described hereinafter.

In the drawings, Figure 1 is an elevation of a key-plate with my improved key in cross-section. Fig. 2 is an elevation of the key in place with its guard-down. Figs. 3 and 4 are respectively side and top elevations.

The shank or handle A of my improved key is formed with a longitudinal slot a for the 15 reception of a guard-plate B. This guard-plate is in turn formed with an angle-slot b and a recess c near the other end, and the front of the guard-plate tapers to conform to the contour of the key-handle. A retaining-rivet 20 e passes through the sides of the handle and loosely through the slot b in the guard-plate, and near the outer end of the handle a rivet d rides loosely in a transverse slot f.

When the guard is not in use, it is folded 25 into the handle with the rivet d resting in recess c; but when the key has been inserted in the lock and turned then the guard can be

thrust forward into the key-slot until the rivet d falls behind its lower end and securely locks the guard in the key-slot, so that the 30 key cannot be turned from the outside; but when it is desired to turn the key on the inside the rivet d is raised from behind the guard, which can then be withdrawn from the key-slot and folded into the handle with the 35 rivet d resting in recess c.

I claim—

1. A key having a slotted body, and a guard-plate mounted in said slot and movable longitudinally and laterally relatively to the 40 body, whereby it is adapted to engage the key-slot, substantially as described.

2. A key having a slotted body, combined with a guard-plate mounted in said slot and having an angular and a transverse slot, a 45 fixed rivet in the key-body engaging the angular slot and a movable rivet adapted to engage the transverse slot of the guard and a corresponding transverse slot of the key-body, substantially as described.

ELMER E. KAUFMAN.
